UNITED STATES PATENT OFFICE.

JOSEPH SHLIEKR, OF HAVERHILL, MASSACHUSETTS, ASSIGNOR TO UNITED SHOE MACHINERY CORPORATION, OF PATERSON, NEW JERSEY, A CORPORATION OF NEW JERSEY.

SHOE-UPPER-HOLDING DEVICE FOR LASTS.

Application filed October 16, 1924, Serial No. 743,961. Renewed February 18, 1927.

In the manufacture of low, or oxford shoes, when the upper is placed on the last, previous to the lasting operation, it is first correctly positioned on the back end of 5 the last, so that its back seam will be exactly in the middle of the back of the last and its top edge will be at the correct distance from the top of the last. When this has been done, it is customary to secure the upper in this 10 position by driving a single tack through the upper, in the middle of or near its back seam, into the last. The upper is then drawn forwardly and towards the bottom of the last, and the shoe is pulled over and lasted 15 in the usual manner.

The use of tacks for temporarily securing the upper in the position intended has been found to be unsatisfactory for various reasons. In pulling the upper down to the 20 last, considerable strain is liable to be placed on the securing tack, and it is not unusual, if the tack is not firmly driven in the last, for the tack to become bent or pulled out, so that the upper will be displaced. Also, 25 even if the tack is firmly held in the last, it often happens that the upper becomes misplaced on the last, particularly through the enlargement of the tack hole due to the yielding of the leather or the thread of the 30 back seam.

Moreover, it is desirable to shape the upper to the last about its rear end, so that when the shoe is finally lasted the top portion of the upper will be drawn as closely 35 as possible to the last. It often happens, however, that the shoe is too loosely lasted at this point, on account of the fact that the workman has to draw the upper to the last, largely by pulling from the edge portion 40 and this shaping at the back is frequently resisted by the resiliency of the counter in the upper, which frequently is not molded to fit the last perfectly. The single tack is of small assistance in properly 45 shaping the upper to the rear end of the last. Further difficulties also arise through the incorrect positioning of the upper with relation to the top of the last, and, while the pattern is designed to have the edge of 50 the upper, at the back, at a certain distance from the top side of the last, it frequently happens that it is not correctly positioned at this point.

The principal objects of my invention are

to avoid the disadvantages inherent in the 55 use of the securing tacks above referred to, and to provide an ordinary wooden last with means for accurately locating the rear end of a low shoe upper in its intended position, and for securely holding it in this position 60 until the lasting operation has been finished, which at the same time will preferably also positively shape the upper about the rear end of the last and hold it in close contact therewith for a substantial distance at each 65 side of the middle of its rear end.

I accomplish these objects by providing a holding and measuring clip which is adapted to be connected to the rear end of the last in a predetermined position and to overlap the upper rear end edge portion of the upper at its middle and to clamp the same firmly to the last.

For a more complete description of my invention, reference is made to the accompanying drawing in which:

Fig. 1 is a side elevation of a last having an upper holding clip, embodying my invention.

Fig. 2 is a back end elevation thereof.

Fig. 3 is a central sectional view at line 3—3 of Fig. 2.

Fig. 4 is a top plan view of the last with the holding clip in position.

Fig. 5 is a similar view with the holding 85 clip removed.

Fig. 6 is a perspective view of the clip.

According to my invention I provide a metal clip 10 of U-shaped form corresponding approximately to the horizontal contour 90 of the upper part of the rear end of the last on which it is to be used, the material of which the clip is made being stiff or adapted to yield but slightly. A post 11 is rigidly mounted on the concave side of the clip at approximately the middle of the middle line thereof, and is extended midway between the sides of the clip generally at right angles to its surface. The clip is also provided with a spring finger 12 at one end, which also extends from the upper edge of the middle of the clip in approximate parallelism with the post 11 and an indicating notch 13 is formed in the clip at the middle of its opposite edge.

The last 14 is provided with a bushed hole, or recess 15, which extends from the middle of the back thereof and parallel to the upper surface of its heel part, said hole being ar-

ranged to receive the post 11 with a close fit. The lower edge of the hole 15 is located preferably where it is desired to position the upper rear edge of the shoe upper, as will be seen. The upper surface of the last is provided with a flat plate 16 having a series of transverse teeth, or notches 17, adapted to be engaged by a tooth 18 on the finger 12, as hereinafter explained.

10 When employing the above described devices, in the operation of lasting an oxford shoe, the fitted upper 20 is placed in position on the last in the usual manner and the clip 10 is then, or previously, placed in position 15 on the last, by inserting the post 11 part way in the hole 15, as in the dotted line position of Fig. 3, in which position the finger 12 will extend over the plate 16 on top of the last with its tooth 18 in engagement therewith. The upper is then positioned on the back of the last, so that its back seam 21 is exactly in line with the middle of the notch 13 and the upper edge of the upper at the top of this seam engages the post 11, 25 in which position the upper will be held at the desired distance from the top of the last, leaving the intended amount for lasting extending beyond the last bottom. The upper is then drawn closely about the back 30 end, at each side, towards the toe, and, while thus held in position, the clip is struck a sharp blow with a hammer, or is forced against the last in any other convenient manner, causing the U-shaped portion of the clip, 35 which extends over the upper, to be firmly engaged with the upper, so as to clamp it against the surface of the last at each side for a substantial distance from the middle of the back, thereby causing the upper and 40 the stiffener, or counter, which is located in this portion of the upper, to be conformed closely to the last at this point and securely held in this position. When the clip is forced against the upper, the spring finger 45 12 will be forced along the plate 16 a correspondingly increased distance and its tooth 18 will be caught by one of the teeth 17, depending on the thickness of the upper, locking the clip in the position to which it 50 was forced, as shown in Fig. 3. The frictional engagement of the post 11 with the sides of the hole 15 may be made sufficient to hold the clip in place without employing the finger 12, the use of which is, however, 55 preferable. The upper will thus be firmly held in position at the back while the lasting operation is completed and, when this has been finished, the clip will be removed, to do which it is merely necessary to pry up the finger 12, so as to disengage the locking teeth, after which the clip may be readily removed.

With the above described device the upper 60 may be quickly and correctly adjusted to the position intended on the last and caused to

conform closely thereto and be securely held in this position while the lasting operation is being finished, without danger of damage to the upper. The device may also be made at small expense and used indefinitely, and upon lasts of considerably varying styles and sizes, the variations in lasts at the points engaged by the clip being slight.

I claim—

1. In combination with a last, a U-shaped clip adapted to be fitted about the rear end of the last and to clamp the top rear edge portion of a shoe upper at each side of the middle thereof against the corresponding portions of the last, and means on said clip arranged to be engaged with the last to locate the clip in predetermined relation thereto and to secure the clip in clamping position.

2. In combination with a last having a recess extending longitudinally thereof from the middle of its rear end and adjacent to the upper surface thereof, a U-shaped clip having its inner side shaped to fit about the back end of the last for substantial distances at each side of its middle line and for a substantial distance from said recess toward the last bottom, to provide an upper clamping portion, and a post mounted on said clip at its inner side and arranged to be closely fitted in said recess when the clip is in clamping position.

3. In combination with a last adapted to receive a shoe upper in a predetermined position thereon and having a recess in the middle of its rear end at the upper edge of the shoe upper when in said position, a U-shaped clip having its inner side shaped to fit about the rear end of the shoe upper adjacent its upper edge, to clamp the same about the end of the last when in position thereon, a post mounted in said clip and arranged to extend into said recess to hold the clip in clamping position and provide a gage for the edge of the upper and means for securing the clip to the last when in said clamping position.

4. In combination with a last adapted to receive a shoe upper in a predetermined position thereon and having a recess in the middle of its rear end at the upper edge of the shoe upper when in said position, a U-shaped clip having its inner side shaped to fit about the back end of the shoe upper adjacent its upper edge, to clamp the same about the end of the last when in position thereon, a post mounted in said clip and arranged to extend into said recess to hold the clip in clamping position, and a finger on said clip arranged to be yieldably engaged with the top side of the last to lock the clip thereto when in said clamping position.

5. A shoe upper clamping member shaped to embrace the upper rear end of a shoe last and having an arm arranged to enter a hole

in the rear end of the last, and means for holding the clamping member in position on the last.

6. A shoe upper clamping member arranged to be carried by a shoe last as a part thereof, shaped to embrace the upper rear end of the last and having means for adjustably attaching it to the last.

7. A shoe last having a clip attached to the upper portion of its rear end arranged to extend downwardly over the upper of a shoe on the last to clamp the upper rear edge of the upper to the last.

8. A shoe last having an adjustable clip attached to the upper portion of its rear end arranged to extend downwardly over the upper of a shoe on the last to clamp the upper rear edge of the upper to the last, and means for holding the clip in different positions corresponding to shoe uppers of varying thickness in order to exert suitable pressure on the shoe uppers. 15 20

In testimony whereof, I have signed my name to this specification.

JOSEPH SHLIEKR.
